UNITED STATES PATENT OFFICE.

HORACE MANN, OF ALBUQUERQUE, NEW MEXICO.

DESIGN FOR A TIRE.

Application filed February 11, 1927. Serial No. 20,697. Term of patent 14 years.

To all whom it may concern:

Be it known that I, HORACE MANN, a citizen of the United States of America, residing at Albuquerque, in the county of Bernalillo, and State of New Mexico, have invented a new, original, and ornamental Design for a Tire, of which the following is a specification, reference being had to the accompanying drawings forming a part thereof.

Figure 1 is a perspective view showing a portion of a tire, and

Figure 2 is a fragmentary plan view showing my new design.

I claim:—

The ornamental design for a tire as shown.

HORACE MANN.
